UNITED STATES PATENT OFFICE

ALBERT S. MACDONALD, OF QUINCY, MASSACHUSETTS, ASSIGNOR, BY MESNE ASSIGNMENTS, TO BAY STATE FISHING COMPANY, OF BOSTON, MASSACHUSETTS, A CORPORATION OF MASSACHUSETTS

WIRE SUPPORT AND GUIDE

Application filed March 23, 1928. Serial No. 263,997.

This invention relates to a device for assisting in the unreeling of wire from a wire coil, which is particularly adapted to guide the wire in such a manner that catching or snarling thereof is avoided so that the wire can continuously be removed from the coil and fed to any suitable point of use.

A device of this character preferably has a wire guiding member so arranged that it conforms to the size of the wire coils and permits the same to be arranged in spirals as the wire passes from the coil to the straight run leading to the point of use. Thus the guiding member preferably may be cylindrical and 15 may have a diameter slightly smaller than the inner diameter of the coil from which the wire is to be removed. This member is preferably arranged in association with certain retaining elements, so that the wire run is put 20 under some tension at the upper end of the guide member and so that the spiral closely conforms to the outer surface of that member at the point where the wire leaves the spiral and follows a more or less straight path.

25 A suitable frame is preferably arranged at either side of the guide member and has a portion extending above the same with an opening adapted to receive the wire run and to provide an auxiliary guide for the same. The upper portion of the main guide member is 30 preferably connected to the frame member in such a manner that additional coils of wire may be readily located in concentric relation to the guide member. Thus a device constructed in accordance with the present invention permits the wire passing from the coil first to follow a spiral path, which has an 35 average diameter somewhat greater than that of the cylindrical guide member, the diameter of the spiral decreasing as the wire approaches the portion of the guide member which is engaged by the retaining means, this retaining means preferably being yieldable or yieldably mounted so that the upper portion 40 of the wire spiral adjoining the point where the wire leaves the guide member preferably conforms closely to the surface of that member. Thus the wire may follow an 45 indeterminate path as it leaves the coil, but 50 it is guided more accurately as its distance

from the coil increases, being positioned close to the guide means as it leaves the same. Thus the portion of the wire adjoining the coil is free to flex and to adjust itself to a position determined by the tension imposed thereon by the pull upon the straight wire run and by its engagement or contact with adjoining wire coils, while the portion of the wire that is leaving the guide means is handled under substantially uniform conditions and follows a quite definite path.

55 In the drawings, which exemplify one embodiment of the invention,

Fig. 1 is a top view of the improved device 60 with a coil of wire disposed upon the same;

Fig. 2 is a side view of the same.

In the accompanying drawings, which 65 illustrate a preferred embodiment of the invention, the numeral 1 designates a support which may conveniently rest upon the floor or the ground or any supporting surface. This support may be of any desired form, being conveniently circular in shape as 70 shown. Support 1 carries a centrally disposed upstanding annular flange 2 which may be secured thereto in any suitable manner. Mounted in telescoping engagement with flange 2 is the upstanding guide member 3; preferably this guide member may be 75 cylindrical in shape and it may conveniently take the form of a sheet metal shell, being secured to flange 2 by fastening elements 4 or the like. A suitable frame 5 is preferably associated with support 1 and member 3 and 80 may be conveniently secured to the former. As shown, this frame is of inverted U-shape, having vertical side bars 6 and an upper cross portion 7.

85 Slidably mounted upon each bar 6 is a clamp 8 which may carry a hand screw 9 adapted to permit the convenient adjustment of the bracket at any desired height in relation to the frame. Each bracket preferably carries a horizontal bar 10, the end portions 90 of the latter being secured to the legs of an open strap metal loop 12 that engages the periphery of the guide member 3. Preferably, when the thumb nuts 9 are tightened 95 the halves of the bracket 8 are drawn to

gether and the loop elements 12 are pulled toward the sides of the frame in such a manner that they grip the upper portion of guide member 3 tightly therebetween. 5 Each of the brackets 8 also carries a retaining element 14. This element preferably is yieldable or yieldably mounted, and as shown may comprise a strip of resilient sheet metal having its inner end 15 inclined upwardly and maintained in yieldable engagement with the outer surface of the guide member 3. The horizontal portion of frame 5 preferably carries an eye 16 which is arranged substantially over the middle of the guide shell 3.

In the use of a device of this character, a coil of wire, designated in general by the numeral 18, may be disposed upon the support 1 in concentric relation to the lower part 20 of guide member 3. In order to permit the convenient disposition of the wire in this manner, the hand screws 9 may be loosened, whereupon the connecting elements 12 are moved upwardly out of engagement with 25 guide member 3, so that the wire coil may be dropped down over this member. The loops 12 are then preferably returned to the positions which they normally occupy, and which are shown in the drawings, the hand 30 screws 9 being tightened so that they maintain the upper part of guide member 3 accurately and rigidly positioned. The resiliency of members 14 permits clamps 9 and connecting elements 12 readily to be returned 35 to their normal positions, the inclination of part 15 defining a comparatively narrow notch through which the wire is drawn as it leaves the shell. The end of the wire which forms coil 18 is brought upwardly and fed 40 through the opening in eye 16, and thence to the point of use. This feeding of the initial end of the wire results in the formation of wire spirals about the guide shell 3. As the wire is drawn from the coil, the lower 45 spiral may, and normally will, have a diameter somewhat greater than the diameter of the shell 3, while the resiliency of the wire and the tension cast thereon will cause the upper portion of the helical part of the 50 wire to conform closely to the curvature of the surface of guide member 3, the angular arrangement of retaining element 14 causing the wire to be held closely against this surface. It is thus evident that the wire follows 55 a helical path as it leaves the coil 18, this path first being indefinitely determined and depending largely upon the exact part of the coil from which the wire is passing, while continued movement of the wire along this 60 helical path, due to the arrangement of retaining member 14, results in the wire conforming closely to a predetermined path, before it passes outwardly in a substantially straight run. It is accordingly evident that 65 the wire gradually merges from a substan-

tially flat coil to a straight run and that there is no sharp point of demarcation between the successive portions of the path which the wire follows, the coiled wire gradually merging into the indefinite helical winding and this coil in turn merging into a more or less definitely determined helical curve or path, which in turn merges into a substantially straight wire run. It is therefore apparent that the minimum of difficulty is encountered in snarling or catching of wire coils upon each other, and it has been found in practice that a guiding device of this character permits the wire to be drawn rapidly and smoothly from a coil without catching or entanglement. 70

While a comparatively high tension may be imposed upon the wire passing through loop 16, substantially all of this tension is opposed by the frictional engagement of the wire with the element 14 and the adjoining portion of guide 3, so that a comparatively light pull is imposed upon the wire convolutions which are wrapped about guide 3. Due to the natural tendency of these wire convolutions to retain substantially the shape originally imposed thereon when formed into the coil 18, they do not tend to wrap tightly about the guide 3; accordingly the wire but loosely engages the latter and there is no substantial snubbing effect. 75

I claim:

1. A device of the class described, comprising a central cylindrical guide, a support at the lower end of the guide adapted to hold a wire coil concentrically arranged about the guide, an element above the support and juxtaposed to the guide to hold the wire in frictional engagement with the surface of the same when it is being drawn from the coil, a frame about the guide, and an opening in the upper part of the frame to receive wire from the guide. 100

2. A device of the class described, comprising a central guide, a support at the lower end of the guide adapted to hold a wire coil concentrically arranged about the guide, an element about the support juxtaposed to the guide to hold the wire in frictional engagement with the surface of the same when it is being drawn from the coil, a frame carried by the support and having a portion above the guide, said portion having an opening 105 to receive wire from the guide. 110

3. A device of the class described, comprising a central guide, a support at the lower end of the guide adapted to hold a wire coil concentrically arranged about the guide, an element above the support juxtaposed to the guide to hold the wire in frictional engagement with the surface of the same when it is being drawn from the coil, a frame extending upwardly at either side of the guide, and means connecting the upper portion of the guide to the frame. 115

4. A device of the class described, comprising a central cylindrical guide, a support at the lower end of the guide adapted to hold a wire coil concentrically arranged about the guide, and elements above the support juxtaposed to the guide to hold the wire close to the surface of the same when it is being drawn from the coil, said elements having surfaces inclined upwardly and inwardly adjoining the guide, a frame extending upwardly at either side of the guide, and means connecting the upper portion of the guide to the frame, said means being vertically movable to permit a wire coil to be dropped about the guide.
5. A device of the class described, comprising a central cylindrical guide, a support at the lower end of the guide adapted to hold a wire coil concentrically arranged about the guide, an element above the support juxtaposed to the guide to hold the wire close to the surface of the same when it is being drawn from the coil, said element being yieldably urged toward the side of the guide cylinder, a frame extending up at either side of the guide, and means normally connecting the upper end of the guide to the frame, said means being movably mounted to permit location of new wire coils upon the support.
6. A device of the class described, comprising a central guide, a support at the lower end of the guide adapted to hold a wire coil concentrically arranged about the guide, and elements above the support juxtaposed to the guide to hold the wire in frictional engagement with the surface of the same when it is being drawn from the coil, a frame connected to the support and having a portion above the guide, said elements being adjustably connected to the frame so that they may be moved out of engagement with the guide.
7. A device of the class described, comprising a central guide, a support at the lower end of the guide adapted to hold a wire coil concentrically arranged about the guide, and yieldable elements above the support movably juxtaposed to the guide to hold the wire close to the surface of the same when it is being drawn from the coil, a frame extending upwardly at either side of the guide, clamps slidably mounted on the frame, connecting elements carried by the clamps and movable therewith from a position wherein they connect the guide and frame to a position above the guide, said yieldable elements being carried by the clamps.

Signed by me at East Boston, Massachusetts, this 9th day of March, 1928.

ALBERT S. MacDONALD.
